SLIDING SCOOTER

Olof Helmer Walgren, Grand Forks, N. Dak.

Application June 6, 1938, Serial No. 212,140

1. Claim. (Cl. 280—23)

This invention relates generally to a sliding scooter of that type of foot-propelled runner-supported vehicle adapted to support one foot of a person while being propelled along by the engagement of the other foot with the ice or snow surface being traveled over.

My invention more particularly relates to the provision of such a sliding scooter that is of simple and strong construction and readily 10 steered and capable of great speed with relatively little effort.

Various other objects and advantages of the invention will be obvious from the following particular description of embodiments of my invention.

The various features of novelty which characterize my invention are pointed out with particularity in the claim annexed hereto and forming a part of this specification, but for a better understanding of the invention, however, its advantages and specific objects obtained with its use, reference should be had to the accompanying drawings and descriptive matter in which I have illustrated and described the best forms of my invention.

25 In the accompanying drawings:

Fig. 1 is a plan view of one form of my invention.

Fig. 2 is a side elevation of the form of the invention shown in Fig. 1.

Fig. 3 is a cross-sectional view on line 3—3 of Fig. 2.

Fig. 4 is a front end view of the form of the invention shown in Fig. 1.

Fig. 5 is a plan view of a modified form of my invention.

Fig. 6 is a side elevation of the modified form of the invention shown in Fig. 5.

Fig. 7 is a cross-sectional view on line 7—7 of Fig. 6.

Fig. 8 is a rear end view of the modified form of the invention shown in Fig. 5.

In the form of the invention shown in Figs. 1, 2, 3 and 4, a main steering and supporting runner 10 is positioned between two balancing side runners 11 and 12. Of these three runners, all of which are preferably made of spring steel, the main runner 10 is of such a length that its forward end 13 extends an appreciable distance beyond the forward ends 14 and 15 respectively of the side runners 11 and 12, while its rearward end 16 extends an even greater distance to the rear of the rear ends 17 and 18 respectively of such side runners 11 and 12. This relatively long main runner 10 facilitates steering, not only

due to its material of readily flexible spring steel and to its manner of one-point vertical support with respect to the frame, as hereinafter described, making it possible to bend the same into the positions shown in dotted lines in Fig. 1, 5 but also due to the fact that the surface-engaging under-side face 19 of the main runner projects, as shown at 20, slightly below the corresponding underside faces 21 and 22, respectively, of the side runners 11 and 12, thus reducing friction by reason of the side runners, in their normal position during operation of the device, being slightly elevated above the surface being traveled over.

To the main runner 10 is secured, as by brackets 15 23, a foot plate 24 which may be covered by a rubber or other suitable mat 25 on which a person rests one foot in use of the device, such mat being securely attached by four split rivets 25' at the corners of the foot plate or in any other 20 desirable manner. As shown this foot plate is located slightly to the rear of the center of the main runner, but it may be positioned at any point to the rear of, and convenient to, the steering post and handle, hereinafter described. At its 25 forward end, the main runner 10 is curved upwardly as at 26, and similarly, at their forward ends, as at 27 and 28 respectively, the side runners 11 and 12 are curved upwardly.

In the form of the invention shown in Figs. 1 30 to 4 inclusive, the main frame comprises a pair of metal strap members 29 and 30 which are secured together, as by rivet or other suitable fastening means 31, for part of their length to form a steering post 32, and which at the bottom 35 of such post diverge outwardly as at 33 to extend horizontally to form a cross bar 34, before being bent downwardly, as at 35, to form legs 36 and 37 for supporting the side runners 11 and 12 respectively the desired distance apart. To the 40 lower end 38 of such leg 36 is secured, as by rivet 38' or by welding or otherwise, a relatively short strap member 39 and such two connected members 38 and 39 are spread apart to embrace the web of the side runner 11 and are pivotally 45 secured thereto through the medium of pivot pin 40. In a similar manner the other leg 37 is pivoted, as at 41, to the other side runner 12, thus rendering the side runners and the device as a whole better adapted for traveling over bumpy 50 surfaces. The upper ends of such steering post strap portions or members 29 and 30 are bent, at a point above the rivet 31, to extend outwardly at substantially right angles to the steering post to form ears 42 and 43 for attaching there- 55

to, by rivets or other suitable fastening means 44, a handle 45 which may be of wood, such as hickory, or any other suitable material, and of any desired dimensions and at any convenient height to be grasped by the person operating the device.

Just before they diverge at 33 near the bottom of the post 32, the strap members 29 and 30 are separated sufficiently to receive therebetween, secured by rivets 45' or by welding or otherwise, the upper end 46 of a central strap brace 47 that extends downwardly a sufficient distance to connect with and support the main runner at a level slightly below the side runners, as previously mentioned. The main runner 10 is embraced by, and rigidly secured as by a rivet 48 between, the lower end of such brace 47 and a relatively short strap member 39 rigidly secured as by rivet 48' or by welding or otherwise to such lower end. Thus the frame is supported vertically from an intermediate point of the main runner 10 solely by the connection 48, and is held in such upright position by braces 49 and 50.

Secured as at 51 to the curved end 26 of the main runner and diverging rearwardly and upwardly therefrom are these pipe or other braces 49 and 50, the rearward ends of which are secured, as at 52 and 53 respectively, to the cross bar 34. A seat 54 has its rear end secured to the cross bar 34 by means of bolts 55 or in any other suitable manner, and has its forward end supported on a block 56 which is in turn supported by the braces 49 and 50, so as to provide a seat of proper dimensions and preferably with a slight upward tilt, as shown at 57.

In the operation of the form of the invention shown in Figs. 1 to 4 inclusive, a person places a foot upon the foot plate 24, holds the handle 45 in the hands and with the other foot engages the ice or snow surface to propel the device along. Steering is accomplished by turning the steering post by means of the handle 45, and thus, through the cross bar 34 and braces 49 and 50, the front end of the flexible spring steel main runner 10 is sprung to produce a turning movement to one side or the other, and in such turning movement the side runners 11 and 12 also participate by reason of their being supported by the frame cross bar through which the turning movement is transmitted from the handle to the main steering runner 10. Since the central runner 10 forms the principal runner for supporting and steering the device, it is shown much longer than the side runners which are for balancing the device and thus preferably are relatively short. It is to be noted that the simultaneous movement and hence continual alignment of the side runners with the main runner permits them to perform their function of balancing the device when moving in a turning direction without any more retarding friction effect than when moving in a straight direction.

In Figure 1 there are shown, in dotted lines, examples of the relative positions (during a turning movement of the device to either side of a straight line direction) of the rear portion of the main steering runner with respect to the front portion of such main steering runner, the side runners, cross bar, steering post, handle, etc. However, it is to be understood that greater or less flexing for greater or less turning movement, and to either one side or the other, is possible than that illustrated in dotted lines in Fig. 1, and it is pointed out that in actual practice it is possible to flex the main spring steel runner 10 so as

to make it even assume a half-circle. Contributing to the extreme flexibility, in addition to the spring steel material of the main runner, is the fact that such main runner is not connected with the frame at any point between the vertical brace 5 point 48 and the horizontal brace connection 51 with the extreme curved end of the main runner. By this construction substantially the entire forward and rear portions of the main runner are free to be bent in response to the handle turning movement, and the point 48 is where the main runner bends in the steering movement.

In the form of the invention shown in Figs. 5, 6, 7 and 8, the reference numeral 10' identifies the main runner and the reference numerals 11' 15 and 12' identify the side runners, corresponding to such parts in the form of the invention shown in Figs. 1 to 4 inclusive, and these runners in this modified form are of the same material, shape and relative dimensions as in the first form 20 hereinbefore described. Also in this modified form, a similar foot plate 24' is attached to the main runner by similar brackets 23' as in the form shown in Figs. 1 to 4 inclusive.

In the form of the invention shown in Figs. 25 5 to 8 inclusive, the main frame comprises a pipe or other tubular member which is bent to form a horizontal handle portion 60 intermediate the upstanding leg portions 61 and 62. If desired a hand grip of wrapper manila rope or other suitable material, as at 63, may be applied to the handle 60. The legs 61 and 62 are shown as being substantially parallel and spaced apart any distance desired between the side runners, which are mounted on the lower ends of such legs 30 35 61 and 62. As shown, the lower end of such tubular leg 61 is split into two portions, which are bent to form two diverging brace members 64 and 65, and the lower end of each of these two brace members 64 and 65 is in turn split and spread 40 apart to form attaching feet 66 and 67 to embrace the web of the side runner supported thereby and thus each of the two side runners is rigidly secured to the tubular frame member by means of the double-split end of one of the leg 45 members 61 and 62.

Rigidly secured as by rivet or other fastening means 68 to the web of the main runner 10 are the strap braces 69 and 70 which diverge upwardly to be secured as by rivets 71 to the legs 50 61 and 62. In the drawings these strap braces are shown as being formed of a single piece bent into U-shape with the horizontal or cross arm portion 72 acting as a brace between the legs 61 and 62, and the free ends of such integral piece 55 secured to the main runner at 68 and diverging upwardly to be secured to the legs, as above explained. Secured as at 73 the curved forward end of the main runner 10 and diverging rearwardly and upwardly therefrom are the pipe or 60 tubular or other braces 74, the opposite ends of which are secured, as at 75, to the legs 61 and 62. A seat 76 has its rear end supported and secured to the cross arm 72 and its forward end supported on a block 77 which is in turn supported 65 on the braces 74. The seat is hinged at 78 and provides a utility compartment 79. Secured to the braces 74 near their connection with the forward curved end of the main runner is a foot rest 80 for the convenience of a person riding as 70 a passenger on the seat 76.

In the form of the invention shown in Figs. 5, 6, 7 and 8, the steering is accomplished by turning the steering post legs 61 and 62 by means of the handle 60, and through the braces 75

74, the front end 13' of the main flexible steel runner 10' is turned and carries with it the side runners 11' and 12' by reason of their being supported by the legs 61 and 62 through which the 5 turning movement is transmitted from the handle 60 to the main steering runner 10'.

In Figure 5 there are shown, in dotted lines, examples of the relative positions (during a turning movement of the device to either side of a 10 straight line direction) of the rear portion of the main steering runner with respect to the front portion of such main steering runner, the side 15 runners, steering post, handle, etc.

Similarly as described in the form of the invention shown in Figs. 1 to 4 inclusive, the main runner in the form of the invention shown in Figs. 5 to 8 inclusive is capable of a wide range of flexing by reason both of its spring steel material and also of its one-point connection at 20 68 with the frame where the main runner bends in the steering movement.

Thus it will be seen that I have devised, in the forms of my invention above set forth, an extremely efficient device for the purpose intended, of relatively few parts, light in weight, quickly responsive to steering movement and capable 25

of great speed with a minimum of effort, yet prevented from overturning, without appreciably increasing the frictional resistance thereby, through the use of spring steel balancing side runners cooperating with the spring steel main 5 supporting and steering runner.

I claim:

A sliding scooter having a frame comprising a tubular member formed of substantially inverted U-shape, providing vertical legs and a horizontal handle portion, relatively short spring steel side runners at opposite sides of said frame, a relatively long spring steel main supporting and steering runner intermediate said side runners and extending an appreciable distance both forward and rearward of said side runners, the lower end of each of said legs being split upwardly and bent to form two diverging brace members, each of said brace members being split and spread apart forming attaching feet embracing the web of a side runner and means for supporting said main runner comprising a brace member rigidly secured to said main runner and diverging upwardly and outwardly and secured to said leg members. 20 25

OLOF HELMER WALGREN.
